UNITED STATES PATENT OFFICE

VIRGIL MATTHEW PYLE, OF STOCKTON, MISSOURI

AGITATOR

Application filed November 16, 1929. Serial No. 407,684.

This invention appertains to new and useful improvements in agitators, mixers or churns, and the same has as its principal object the provision of a mixing attachment 5 which can be readily applied to fruit jars of the screw cap variety.

Other important objects and advantages of the invention will become more apparent to the reader after considering the invention as 10 described and claimed hereinafter.

In the drawings:

Figure 1 represents a side elevational view of the novel attachment and placed on a fruit jar.

15 Figure 2 represents a side elevational view of the novel agitator detached from the jar.

Figure 3 represents another side elevational view of the novel agitator applied to a fruit jar.

20 Figure 4 represents a top plan view of the agitator associated with a fruit jar.

Figure 5 represents a sectional view taken substantially on line 5—5 of Figure 2 and looking in the direction of the arrow.

25 Figure 6 represents a fragmentary detail sectional view of the operating means.

Referring to the drawings, wherein like numerals designate like parts, it can be seen that the device is to be associated with the receptacle commonly known as a "fruit jar" and this in the drawings is denoted by numeral 5.

The attachment includes a cap 6 which can be screwed onto the usually threaded neck of 30 a fruit jar 5 and secured to the top of the cap 6 is an inverted U-shaped bracket 7 through which the elongated shaft 8 is journaled. A substantially rectangular shaped frame, which serves as a handle is denoted by numeral 9 and is secured to the top of the cap 6 in an upright position.

This frame is provided with an offset 10 through which the upper portion of the shaft 8 extends. To this offset portion 10 of the 45 frame a crown gear 11 is rotatably secured and this crown gear meshes with a pinion 12 carried by the shaft 8. This gear 12 also serves as a stop to limit the movement of the shaft 8, as the same bears against the bight 50 portion of the U-shaped bracket 7.

The lower end of the shaft 8 has a block 13 secured thereto of polygonal shape and the various sides of this block have diagonally disposed slots 14 therein for the reception of the rectangular shaped blades 15. These 55 blades are approximately the same length as the blocks 13, thus terminating at their upper and lower ends substantially flush with the upper and lower ends of the block 13.

In this manner, a substantial screw action 60 is derived from the rotation of the block 13.

It will thus be seen that the device offers a simple attachment which can be readily applied to fruit jars, and in the event the fruit jar breaks, another may be replaced 65 at the usual cost of a "fruit jar", thus dispensing with the necessity of purchasing a receptacle especially devised for a particularly constructed agitator.

While the details of this invention have 70 been specifically set forth herein, it is to be understood that changes may be resorted to within the scope of the appended claim.

Having described my invention, what is 75 claimed as new is:

In an agitator of the character specified, an attaching member, an inverted U-shaped bracket secured to the attaching member and having a horizontally disposed bight portion spaced above the support, an agitator having 80 a shaft extending through said support and the bight portion of said bracket and provided with a gear, a frame mounted rigidly on said support in a plane at right angles to the plane of said bracket and having a lateral 85 extension overhanging said gear and the bight portion of said bracket and rotatably receiving the upper portion of said shaft, and a gear rotatably carried by the lateral extension of the frame and having means whereby 90 the frame may be rotated.

In testimony whereof I affix my signature.

VIRGIL MATTHEW PYLE.
